CASING FOR A SINK ATTACHED DISH WASHER UNIT

Charles J. Manville, Pontiac, Mich., assignor to Manville Manufacturing Corporation, Pontiac, Mich., a corporation of Michigan

Filed Aug. 9, 1961, Ser. No. 66,267

Term of patent 14 years

(Cl. D91—3)

Fig. 1.

Fig. 2.

Fig. 3.

Fig. 5.

Fig. 4.

Fig. 6.

FIG. 1 is a front elevational view of a casing for a sink attached dish washer unit, showing my new design.

FIG. 2 is a top plan view thereof;

FIG. 3 is a side elevational view thereof looking from the lefthand side of FIG. 1;

FIG. 4 is a cross-sectional view thereof taken on line 4-4 of FIG. 1;

FIG. 5 is a rear elevational view thereof; and

FIG. 6 is a side elevational view thereof taken from the righthand side of FIG. 1.

I claim:

The ornamental design for a casing for a sink attached dish washer unit, as shown.
